Primary Examiner — Sheryl Lane
Assistant Examiner — Nicole C Shiflet(74) *Attorney, Agent, or Firm* — Patterson Thuente Pedersen, P.A.(57) **CLAIM**

We claim the ornamental design for a display screen or portion thereof with graphical user interface, as shown and described.

DESCRIPTION

FIG. 1 is a front view of a display screen or portion thereof with graphical user interface according to an embodiment of the invention.

FIG. 2 is a front view of FIG. 1 depicted on a device.

FIG. 3 is a front view of a display screen or portion thereof with graphical user interface according to another embodiment of the invention; and,

FIG. 4 is a front view of FIG. 3 depicted on a device.

The broken lines in the drawings illustrate portions of the display screen or portion thereof with graphical user interface and a device that form no part of the claimed design.
